UNITED STATES PATENT OFFICE.

HENRY SIEBEN, OF KANSAS CITY, MISSOURI, ASSIGNOR, BY DIRECT AND MESNE ASSIGNMENTS, TO FIRE AND GAS APPLIANCES CO. A CORPORATION OF MISSOURI.

GAS-CONTROLLING APPARATUS.

1,033,958.

Specification of Letters Patent. Patented July 30, 1912.

Application filed April 22, 1910. Serial No. 557,943.

To all whom it may concern:

Be it known that I, HENRY SIEBEN, a citizen of the United States, residing at Kansas City, in the county of Jackson and State of Missouri, have invented certain new and useful Improvements in Gas-Controlling Apparatus, of which the following is a specification.

My invention relates to improvements in gas-controlling apparatus, and my object is to provide new and novel apparatus whereby the supply of gas or other fluid entering a building through the service-pipe thereof, may be readily cut off in case of fire, or at any other time desired.

The apparatus embodies a self-closing valve for controlling the flow of fluid through the service-pipe, manually-operable means whereby said valve may be controlled at a point distant therefrom, and fusible means which when subjected to a predetermined degree of heat will melt and permit the valve to automatically close.

In order that the invention may be fully understood, reference will now be made to the accompanying drawings in which:

Figure 1 is a side elevation partly in section of my improved apparatus. Fig. 2 is a detail vertical section on line II—II of Fig. 1. Fig. 3 is a section on line III—III of Fig. 2, with a portion of a conduit added. Fig. 4 is a central vertical section of the valve on line IV—IV of Fig. 1. Fig. 5 is a detail perspective of a bracket employed in carrying out the invention. Figs. 6 and 7 are horizontal sections on lines VI—VI and VII—VII, respectively, of Fig. 1. Fig. 8 is a front elevation of a box employed in carrying out the invention. Fig. 9 is an end view of an adjustable elbow employed in carrying out the invention.

1 designates a service-pipe for conducting fluid from the main (not shown) into a building, the front wall 2 of which only is shown.

3 designates a valve for controlling the flow of fluid into the building through the service-pipe 1. Said valve consists of a shell 4 having a port 5 for the passage of the fluid, a sliding-gate 6 for closing said port, a stem 7 for controlling said gate, and a spring 8 tending to force the stem downward to close the gate, which has a pin-and-slot connection 9 with said stem. Shell 4

is provided at its lower end with a tubular 55 guide 10, closed by a screw-cap 11, and adapted to receive the lower end of stem 7 as the same approaches the end of its downward stroke. The upper portion of shell 4 has a stuffing-box 12 through which the stem 60 7 extends and said upper portion has, also, a pair of oppositely-extending, diametrically-opposed arms 13 to carry a bracket 14. Gate 6 is provided with a lug 15 projecting therefrom and having a beveled side 16 for 65 engaging a correspondingly beveled portion 17 of the stem which when the valve closes pushes the gate firmly against its seat 18, the valve-stem being prevented by guide 10 from springing back under the pressure exerted 70 by its beveled portion 17 pushing against the beveled side 16 of lug 15. Gate 6 is provided at its lower end with a blade 6^a, so that when it closes said blade will scrape seat 18 clean of any foreign matter which 75 might interfere with proper closing of the gate. Spring 8 is assisted in closing the valve by a lever 19 and a weight 20, which latter is adjustably-secured to the free end of the former by a sleeve 21 and a set-screw 22. 80 Lever 19 is fulcrumed upon a bolt 23, and has a longitudinal slot 24 through which the upper reduced terminal 25 of the stem extends.

Bracket 14 comprises a circular base 26 85 having a pair of diametrically-opposed, upwardly-extending arms 27, provided at their upper ends with tubular extensions 28 having bifurcated portions 29. One of the arms 27 also has a vertical extension 30 to carry 90 bolt 23. Base 26 has marginal segmental slots 31, through any oppositely-disposed two of which a pair of screws 32, engaging arms 13 may project. By thus mounting the bracket upon arms 13 said bracket may be 95 turned to face the tubular extensions in almost any direction, to receive the lower ends of a pair of conduits 33.

34 designates a nut having a thread 35 extending into a spiral groove 7^a in the upper enlarged portion of stem 7, to actuate said stem as will hereinafter appear. Nut 34 is connected by a fusible substance 36 to the hub 37 of a sprocket-wheel 38, which extends between the diametrically-opposed 105 bifurcated portions 29, and is held thereby from vertical movement with stem 7. Hub 37 has peripheral perforations 39 so that

flames may enter therein and impinge against the fusible substance 36 to melt the same.

The sprocket-wheel 38 is engaged by a 5 perforated tape 40 attached at its ends to the lower ends of a pair of cables 42, extending through the tubular extensions 28 and the conduits 33, and attached at their upper ends to a similar tape 43 extending 10 half-way around a sprocket-wheel 44, provided with a handle 45 whereby it may be actuated. Sprocket-wheel 44 is mounted upon a shaft 46 journaled in a box 47 provided with a hinged door 48, so that access 15 may be had to the handle 45 for the purpose of turning sprocket-wheel 38 to manually close the valve. Door 48 is provided with a staple 49 to receive the slotted end of a hasp 50 loosely secured to the upper side 20 of the box, so that its slotted end may be placed in position over staple 49, and secured by a padlock 51, to prevent irresponsible persons from gaining access to handle 45 to tamper with the same. Tampering 25 with handle 45, is further guarded against by providing the same with a staple 52 adapted to abut against a staple 53 or a staple 54 in the box, and be locked in engagement therewith by a padlock 55. Door 30 48 has grooves 56 therein, to weaken the same, so that access may be readily had to handle 45 in case of a fire by breaking said door, after which either of the staples through which the hasp of lock 55 extends, 35 may be broken to release the handle 45. Sprocket-wheel 44 is of greater diameter than sprocket-wheel 38, so that the latter will be turned one revolution by turning the former about two-thirds of a revolution, or 40 sufficiently to swing handle 45 from staple 52 to staple 54, as one revolution of sprocket-wheel 38 is necessary to close valve 3 when the parts are made in about the proportions shown in the drawings.

45 Cables 42 which consist preferably of fire-proof material are further protected by the conduits 33, which latter have adjustable elbows 57 so that they may be extended in any desired direction. Elbows 57 consist 50 of adjustable sections 58 and 59, which are pivotally connected by bolts 60, carrying grooved rotors 61 to guide the cables 42 through the conduits.

In practice, the valve is held in the open 55 position shown in Fig. 1 by nut 34. Should a fire occur in the building, or should it be desirable for any reason to cut-off the flow of fluid through the service-pipe 1, any authorized person can promptly perform this 60 operation by opening the box 47, grasping handle 45, and swinging it around until stopped by the staple 54. This movement of the handle rotates wheel 38 and causes it

through the intermediary of the connecting parts to close the valve. Should the fusible 65 substance 36 become heated to the melting point before the fire was discovered, it would free nut 34 from wheel 38, and thus permit spring 8, lever 19, and weight 20 to automatically close the valve. After the 70 fire had been extinguished and the fusible substance 36 between nut 34 and wheel 38 had been renewed, the valve could be opened by moving handle 45 back to its original position or until its staple 52 contacted with staple 53.

While I have shown the preferred form of my invention, I, of course, do not limit myself to the exact construction and arrangement of parts as shown and described, 80 as it is obvious that changes can be made without departing from the spirit or scope of the appended claims.

Having thus described my invention, what I claim is:

1. In an apparatus of the character described, a service-pipe for conducting fluid into a building, a valve to control the flow of fluid through said pipe, a wheel on said valve to open and close the same, means extending at a distance from said wheel for turning the same in either direction, conduits for protecting said means, and a bracket adjustably-secured to the valve, said bracket having tubular portions to communicate with the conduits and bifurcated portions to prevent lateral movement of the wheel.

2. In an apparatus of the character described, a service-pipe for conducting fluid into a building, a valve to control the flow of fluid through said pipe, manually-operable means extending at a distance from said valve to close the same, a box inclosing that portion of said means most remote from the valve, said box having a grooved breakable portion, and means for locking said box in closed position.

3. In an apparatus of the character described, a service-pipe for conducting fluid into a building, a valve to control the flow of fluid through said pipe, said valve having a spiral groove, a nut engaging the grooved portion of said valve to open or close the same, a wheel for actuating said nut, and a bracket loosely engaging opposite sides of said wheel to prevent the same from moving in any other than a rotary direction.

In testimony whereof I affix my signature, in the presence of two witnesses.

HENRY SIEBEN.
